UNITED STATES PATENT OFFICE.

EUGÈNE SCHNEIDER, OF LE CREUZOT, FRANCE, ASSIGNOR TO SCHNEIDER & CIE., OF PARIS, FRANCE, A LIMITED JOINT-STOCK COMPANY OF FRANCE.

WHEELED CARRIAGE FOR GUNS HAVING A LARGE HORIZONTAL ANGLE OF FIRE.

1,316,196.

Specification of Letters Patent. Patented Sept. 16, 1919.

Application filed February 14, 1918. Serial No. 217,189.

To all whom it may concern:

Be it known that I, EUGÈNE SCHNEIDER, a citizen of the French Republic, and a resident of Le Creuzot, Saone-et-Loire, France, 5 have invented a new and useful Improvement in Wheeled Carriages for Guns Having a Large Horizontal Angle of Fire, which invention is fully set forth in the following specification.

10 This invention has for its object to provide an improved wheeled gun carriage having a large angle of horizontal fire.

The improved gun carriage is characterized essentially by the combination of an 15 chored plates for supporting the wheels, with a tensile member or tie of constant length but deformable, located between the said plates and the carriage trail. This tie may be pivoted at its ends at two fixed points 20 on the said plates, and bears at a variable intermediate point upon a guiding device carried by or formed on the carriage trail. As the result of this combination, if the carriage is constructed in such a manner that the 25 trail alone or the entity comprising the trail and the wheeled axle, is able to turn on a real or imaginary pivot equidistant from the points of attachment of the deformable tie, the gun carriage will turn about the point 30 of intersection of two vector radii of an arc of an ellipse, having for its foci the points of attachment of the tie to the plates, said arc by reason of the dimensions of the gun carriage coinciding practically with the arc 35 of a circle described by the trail around the center on which it turns. In all positions the apex of the deformable tie and the two points of attachment of the latter will constitute a triangle for maintaining the 40 stability of the gun carriage during firing. The changes in position will not require any modification of the anchorage and can be produced by merely displacing the carriage trail. The deformable tie of constant length, 45 instead of being attached at its ends to two fixed points of the anchoring plates and guided on the trail, may inversely be attached at its ends to the trail and be guided on members located at the foci of the ellipse 50 formed on the plates.

Several constructional embodiments of this

invention are illustrated in the accompanying drawings in which:

Figures 1 and 2 are respectively a side elevation partly in section and a plan of one 55 embodiment of the invention.

Fig. 3 is a diagram showing in full lines the gun carriage in mid position for training the gun, and also showing respectively in dash and dot lines and dotted lines the same 60 gun carriage in two extreme positions symmetrical to the said mid position.

Figs. 4 and 5 are respectively a side elevation partly in section and a plan of another embodiment. 65

Fig. 6 is a part horizontal section on the line VI—VI of Fig. 4.

Fig. 7 is a plan of a further embodiment of the invention.

Fig. 8 is a plan of another embodiment of 70 the invention, and

Fig. 9 is a diagram illustrating a particular manner of applying any one of the embodiments above referred to.

In all these figures, A is the gun carriage 75 axle, B—B are the wheels and C is the trail of a wheeled carriage of any known type.

The gun carriage in the firing position rests with its wheels on plates D, D, which are anchored to the ground by known means, 80 for instance by means of stakes E.

In all these embodiments the gun carriage is constructed in such a manner that the trail C is capable of turning on a center O. The wheeled axle A, B—B may move with the 85 trail around said center or remain stationary. In the latter case the trail is jointed to the axle by means of a vertical pivot.

According to this invention the carriage comprises a deformable tie of constant 90 length located between the carriage trail and two fixed points F of the plates, said points being equidistant from the center O.

In the embodiments shown in Figs 1 to 6, the said tie may bear at a variable intermediate point upon a guiding member G carried by or formed on the carriage trail. The tie which may consist wholly of a cable or of a chain passing over a pulley or a pinion pivoted to the carriage trail, is 100 preferably constructed as shown in Figs. 1, 2, 4, 5 and 6. In that construction two

stays each consisting of two sections H , H^1 connected together by a turn-buckle h , are jointed at their section H to the fixed point F of the corresponding plate, while they are 5 each connected at their section H^1 to one of the ends a pitch chain I passing over a pinion G pivoted on the trail spade.

In the embodiment shown in Figs. 1 and 2, the anchoring plates D are formed each on 10 its upper face with a raised edge d constituting a cylindrical bearing wall for the corresponding wheel B . In the turning movements of the wheeled axle and trail around the center O , the two wheels remain 15 each bearing against the corresponding guiding edge d . Assuming the gun carriage is ready for firing in the mid position shown in Figs. 1 and 2, and indicated in full lines in the diagram of Fig. 3 (position I), then 20 by moving the gun trail, the whole of the wheeled axle and trail can be moved into the extreme positions II and III (Fig. 3) or into any other intermediate position.

In practice, the arc of the ellipse having 25 its foci at the points F , F , which is described in those movements by the supporting point g of the deformable tie upon the member G , will substantially coincide with an arc of a circle described from the point O as center with the radius $O-g$.

The means for operating the turning movement of the gun carriage may comprise for instance the parts shown in Figs. 1 and 2. The pinion G on which the deformable 35 member of constant length (the pitch chain I) is journaled in the gun trail, is formed on the upper edge of its hub with a series of projections G^1 alternating with recesses G^2 . In the pinion there is slidably mounted 40 a pin J formed with a square portion J^1 , guided in the trail, and a block J^2 carrying a pin K on which is pivoted intermediately of its length a training lever L . One end of this lever is pivoted at L^1 to the carriage 45 trail. A shoulder M on the pin J is formed on its underside with projections M^1 engaging in the rest position in the recesses G^2 . So long as the projections M^1 are engaged in the recesses G^2 , the pinion G is locked in 50 position. If on the contrary by raising the lever L , the projections M^2 are moved out of the recesses G^2 , the pinion G is able to revolve freely around the pin J , when by 55 means of the training lever L the whole of the trail and wheeled gun carriage is turned in the horizontal plane.

The corrections in the training movement may be effected by any known means, for instance by sliding the trail C along the axle 60 A , which is suitably curved for this purpose.

In the embodiment shown in Figs. 4 and 5, the anchoring plates D , D comprise each along its major axis, a channel D^1 in which 65 the corresponding wheel is engaged, so that

the wheeled axle remains stationary during the training movements and the trail alone is turned horizontally around a vertical pivot N , N by means of which it is jointed to the axle A .

70

For effecting considerable changes of training the gun may be turned as in the preceding examples, by means of the rear training lever L . For small corrections of the training, it may comprise the mechanism 75 shown in Figs. 4 and 6.

The pinion G is mounted on a square portion J^1 of a pin J^1 , J , which is capable of being lifted vertically by means of the block J^2 by the training lever L . The upper portion J of the pin J^1 J is tubular and is capable of turning on a stud j^2 formed under the block J^2 . On this tubular portion J there is mounted a helical pinion P formed on its hub with projections p with which there 85 can be engaged corresponding projections formed on the underside of a collar j of the pin J^1 J . When this engagement is produced by depressing the training lever L , the carriage trail may be turned for the 90 purpose of correcting the training, by actuating the pinion P by means of gearing such as $Q-R-S-s-t-T$.

In order to prevent any forward displacement of the wheels B during firing, 95 wedging blocks U may be located in a known manner on the anchoring plates.

The deformable tie of constant length that connects the plates for the wheels to the carriage trail, instead of being fixed to 100 the two points of those plates constituting the foci of the ellipse while the said tie is movable on the carriage trail, may inversely be fixed to the trail and be movable on devices located at the two fixed points of the 105 plates.

In a construction embodying this principle shown in plan in Fig. 7, guiding devices such as rollers F^1 for guiding a non-rigid portion H^2 of the deformable tie of 110 constant length, are mounted on vertical axle pins f , f , at the two fixed points F , F of the plates D for the wheels. H^2 may be a cable the two ends h^2 , h^2 of which consist of hooks engaging in eyes of the rigid sections H of the tie. The sections H^1 may be hooked to fixed attachments h^1 of the trail.

In the embodiment shown in Fig. 8, the non-rigid section H^2 of the deformable tie consists of a pitch chain moving over pinions F^1 mounted on axle pins f at fixed points of a continuous circular wheel plate d . The section H^2 is further guided on a pinion V mounted on an axle pin v projecting from the plate D at its center O . 120 125

It will be understood that the turning movements of the gun for changing the training may be effected by actuating the pinion V or one of the pinions F^1 .

As shown in the diagram of Fig. 9, there 130

may be arranged at suitable points of a complete circumference on a wheel plate D, a plurality of pairs of foci F, F constituting as many points of jointing or guidance for 5 the deformable tie of constant length. By varying the points of attachment of the tie, it is possible to vary all around the horizon the sector in which the gun carriage can be turned by pivoting around the center O 10 of the plate, without changing the attachments or the guides.

The carriage trail may for example as shown in Fig. 1, be provided with attaching members W, for fixing the ends of the de- 15 formable tie during transport.

What I claim is:—

1. In combination, a wheeled gun carriage having a trail provided at the end resting on the ground with a guide pulley, 20 anchored shoe plates for supporting the carriage wheels and a horizontally arranged tie having its ends secured to said plates and having a deformable portion running over said pulley the axis of which remains 25 perpendicular to the plane containing both branches of the tie for all angular firing positions of the trail.

2. In combination, a wheeled gun carriage having a trail provided at the end 30 resting on the ground with a guide pulley, anchored plates for supporting the carriage wheels, and a deformable, horizontally positioned tie adapted to connect said pulley and plates consisting of adjustable rod por- 35 tions pivotally connected to said plates, and a flexible portion running over said pulley.

3. In combination, a wheeled gun carriage having a trail provided at the end resting

on the ground with a guide pulley, anchored plates for supporting the carriage wheels, 40 a deformable, horizontally positioned tie adapted to connect said pulley and plates consisting of adjustable rod portions pivotally connected to said plates and a flexible portion running over said pulley, and means 45 for locking said pulley against rotation for firing.

4. In combination, a wheeled gun carriage having a trail provided at the end resting on the ground with a guide pulley, anchored 50 plates for supporting the carriage wheels, a deformable, horizontally positioned tie adapted to connect said pulley and plates consisting of adjustable rod portions pivotally connected to said plates and a flexible 55 portion running over said pulley, manually-operated gearing for rotating said pulley to adjust the training of said gun, and means for locking said pulley against rotation for firing.

5. In combination, a wheeled gun carriage having a trail, anchored shoe plates for supporting the carriage wheels, a horizontally arranged tie connecting the end of the trail resting on the ground with said plates, said 65 tie having a deformable portion, and pulley means over which said tie runs, the branches of said tie remaining in the same horizontal plane for all angular firing positions of the trail.

In testimony whereof I have signed this specification.

EUGÈNE SCHNEIDER.
